(57) **CLAIM**

The ornamental design for a brass valve for stop box, as shown and described.

DESCRIPTION

FIG. 1 is an upper front right perspective view of a brass valve for stop box embodying my new design;

FIG. 2 is a lower front left perspective view thereof;

FIG. 3 is an upper top left perspective view thereof;

FIG. 4 is a lower front right perspective view thereof;

FIG. 5 is a top plan view thereof;

FIG. 6 is a bottom plan view thereof;

FIG. 7 is a front elevation view thereof;

FIG. 8 is a rear elevation view thereof;

FIG. 9 is a left side elevation view thereof; and,

FIG. 10 is a right side elevation view thereof.

The broken line showing of parts of the drawings is included for the purpose of illustrating use and environment and forms no part of the claimed design.
